UNITED STATES PATENT OFFICE

163,463

DESK TRAY

James T. Lewis, Arlington, Va.

Application February 6, 1950, Serial No. 7,766

Term of patent 14 years

(Cl. D74—1)

To all whom it may concern:

Be it known that I, James T. Lewis, a citizen of the United States of America, and a resident of the city of Arlington, county of Arlington, State of Virginia, have invented a new, original, and ornamental Design for Desk Tray, of which the following is a specification, reference being had to the accompanying drawings, forming part thereof, wherein:

Fig. 1 is a perspective view of a desk tray, showing my new design;

Fig. 2 is a rear end view;

Fig. 3 is a bottom view;

Fig. 4 is a front end view; and

Fig. 5 is a side view.

I claim:

The ornamental design for a desk tray, substantially as shown.

JAMES T. LEWIS.
